UNITED STATES PATENT OFFICE.

HAROLD J. LOCKHART, OF PARKERSBURG, WEST VIRGINIA, ASSIGNOR TO THE PARKERSBURG RIG & REEL COMPANY, OF PARKERSBURG, WEST VIRGINIA, A CORPORATION OF WEST VIRGINIA.

SAND-REEL DRIVE.

1,402,237.

Specification of Letters Patent. Patented Jan. 3, 1922.

Application filed December 1, 1920. Serial No. 427,601.

To all whom it may concern:

Be it known that I, HAROLD J. LOCKHART, a citizen of the United States, residing at Parkersburg, in the county of Wood and State of West Virginia, have invented certain new and useful Improvements in Sand-Reel Drives, of which the following is a specification.

This invention relates to sand reel drives, and it comprises a main drive shaft, a sprocket wheel loosely mounted thereon, a clutch keyed to said shaft and adapted to lock said sprocket wheel thereto, a sand reel shaft, a friction clutch having one element secured to said shaft, the other element being loosely mounted thereon, a sprocket wheel carried by said loosely mounted element, a chain passing over said sprocket wheels, a brake engaging said first mentioned clutch element, and controlling means for said friction clutch and said brake whereby one of said members is rendered inoperative when the other is brought into operation.

In prior constructions, the sand reel shaft of a well rig has been driven from the band wheel on the main shaft by a friction drive. One end of the sand reel shaft is mounted in a bearing in a pivoted lever and this end of the shaft carries a pulley which is adapted to engage the periphery of the band wheel to drive the sand reel shaft. This construction has several disadvantages. The fixed member supporting the opposite end of the sand reel shaft is generally provided with a bearing having an enlarged opening for the reception of the shaft, whereby the shaft may accommodate itself to the various positions it must assume when the pivoted lever supporting one end of the shaft is moved. The construction is disadvantageous as the shaft is so mounted that considerable play is permitted and power lost.

In addition, the frictional engagement of the pulley on the end of the sand reel shaft with the band wheel, which is made of wood, causes uneven wear on the band wheel and eventually causes slipping of the drive belt which is arranged around the band wheel.

A frictional drive for the sand reel shaft is advantageous as a sand reel drive should be so arranged that undue strain will not be imposed on the sand line in case the bailer

should become wedged in the hole. This cannot be accomplished with a positive drive and some sort of friction drive, or its equivalent, is necessary.

In the present invention, I provide a clutch element loosely mounted on the sand reel shaft, and this element is positively driven from the main shaft by a sprocket and chain drive. The other element of the clutch is secured to the sand reel shaft, and the sand reel shaft is coupled to the main shaft by the friction clutch.

It will be noted that the operator can obtain any desired pull upon the sand reel line by changing the force on the clutch lever to produce friction upon the friction clutch rings. The clutch lever must always be held in operative position with a certain amount of force to maintain the clutch element in engagement, and should the operator release the clutch lever, pressure on the friction rings is automatically released, thus relieving any undue strain upon the sand line.

In the accompanying drawings, I have shown one embodiment of the invention. In this showing:

Figure 1 is a plan view of a portion of a well rig, showing the main shaft and the sand reel shaft,

Figure 2 is a vertical sectional view on line 2—2 of Figure 1,

Figure 3 is a side elevation of the construction shown in Figure 2,

Figure 4 is a detail view of the clutch and brake operating levers, and,

Figure 5 is a transverse sectional view of a portion of the main drive shaft.

Referring to the drawings, the reference numeral 1 designates a suitable support or framework on which the rig is mounted. The band wheel 2 is mounted on main shaft 3, and is adapted to be driven from any suitable source of power by a belt (not shown), in the usual manner. The main shaft is mounted in bearings 4, suitably supported from the framework and provided with braces 5. As shown, the band wheel is provided with an enlarged hub 6, over which passes ropes or belts 7 employed in operating other parts of the well rigging apparatus. A pair of sprocket wheels 8 and 9 are mounted on the main shaft. The latter is adapted to drive other parts of the rigging appara-

tus through the provision of a chain (not shown). As the sand reel shaft is never in operation when any other part of the rig is being used, a single clutch 10 is employed 5 to control the two sprocket wheels 8 and 9. This clutch is keyed to the shaft to revolve therewith, and it may be moved to the extreme right or left to cause engagement of one of the sprocket wheels with the shaft, or 10 it may be retained in neutral position, shown in the drawings. The clutch is operated by a pivoted lever 11 secured thereto and pivoted on a bracket 12. The lower end of the lever is secured to a link 13 connected to one 15 end of a control lever 14.

The sand reel shaft 15 is mounted in suitable bearings 16, and provided with braces 17. When the sand reel shaft is to be used, the clutch 10 is moved to the extreme left, in Figure 5 of the drawings, in 20 engagement with the sprocket wheel 8. As shown, a sand reel pulley 18 is mounted on the shaft, and is adapted to receive the sand line to which the bailer is attached. One 25 element 19 of a clutch is fastened to the shaft, and is adapted to revolve therewith. The clutch is of the friction type provided with an engaging element 20 having friction rings 21. The movable element is carried 30 by a collar 22, which is loosely mounted on the sand reel shaft, and when the collar is moved toward the fixed element of the clutch, the rings are forced into engagement by means of pivoted levers 23 and links 24. 35 A sprocket wheel 25 is mounted on the collar 22 and this sprocket wheel is driven from the sprocket 8 by a chain 26. The friction clutch is controlled by a substantially Y-shaped pivoted member 27, which is 40 secured to each side of the collar, as at 28, and pivoted at its lower end, as at 29. A link 30 is connected to this Y-shaped member intermediate its ends, and this link is also connected to one arm 31 of a bell crank 45 lever. The bell crank lever is pivoted at 32 and provided with an arm 33, which is secured to the link 34. The link 34 extends backwardly beneath the main shaft and is connected to a pivoted link 35 having a link 36 connected to its opposite end.

A brake band 37 is arranged around the 55 fixed element 19 of the clutch. The ends of the brake band are secured to links 38 and 39 respectively, the ends of the links being screw-threaded and provided with nuts 40 and 41, whereby the brake band may be adjusted. The link 38 is secured to an arm 42 of a bell crank lever, and the link 39 is secured to the other arm 43. As shown, 60 the arm 43 of the bell crank lever is considerably longer than the arm 42, and when the lever is moved on its pivot, the end 44 of the brake band, which is secured to the link 39, is moved farther than the end 45, 65 thus loosening or tightening the band. The

bell crank lever is pivotally mounted in a bracket 46, being pivoted as at 47. A link 48 is secured to one arm 43 of the bell crank lever, and is connected to the clutch lever in any suitable manner. As shown, it is 70 connected to the arm 33 of the bell crank lever which connects the clutch to the link 34.

The operation of the device is as follows:

When the sand reel shaft is to be driven, 75 the clutch 10 is engaged with sprocket wheel 8 to drive the collar 22 through sprocket wheel 25 and chain 26. The sand line descends by gravity in the usual manner, the weight of the bucket being sufficient to draw the line 80 down into the well. During the descending of the bucket, the friction clutch is disengaged, permitting the sand reel shaft to run free. When the sand reel shaft is to be drawn up, the friction clutch is engaged 85 by moving the link 34 in the direction of the arrows in Figures 1 and 4 of the drawings. The bell crank lever 31, 33 is moved in the direction of the arrow, swinging the Y-shaped member 27 inwardly toward the 90 fixed element 19 of the clutch through the provision of link 30 and causing the friction disks to engage.

When the clutch is operated, the link 48 connecting the brake band is also moved 95 in the direction of the arrow, swinging the bell crank lever 42, 43 on its pivot, and moving the ends 44 and 45 of the brake band. Referring to Figure 2 of the drawings, it will be seen that the movement of the end 100 44 tends to loosen the brake band, while the movement of the end 45 tightens the band. However, the end 44 moves several times as far as the end 45 so that the net result is to loosen the band and release the brake 105 when the clutch is engaged.

When the levers are moved in the opposite direction to release the clutch, and the movement of the link 48 is reversed, the end 44 of the brake band is tightened, and the end 110 45 loosened, the net result being that the band is tightened and the brake applied.

In the actual use of the device, the brake band must be first adjusted so that it will 115 engage the fixed element 19 of the clutch when the clutch is out of engagement and will be released when the clutch is engaged.

It will be observed that two separate and distinct modes are available for stopping the descent of the bailer. When the operator desires to stop the descent of the bailer, the link 36 may be moved in the proper direction to engage the brake band 37 and the fixed element 19 of the clutch, thus stopping the revolution of the sand reel shaft 15. 120 Should any of the brake mechanism become disengaged or damaged, the operator may stop the descent of the bailer by moving the link 36 in the opposite direction to engage the clutch, and merely applying sufficient 125

pressure to overcome the force of gravity, and thus check its descent entirely or to any degree desired.

It will be apparent that by means of the present construction, I have provided a sand reel drive wherein the pivoted sand reel lever supporting one end of the sand reel shaft is eliminated, and at the same time, all the advantages of a friction drive are retained.

10 It is to be understood that the form of my invention herewith shown and described is to be taken as a preferred example of the same, and that various changes in the shape, size, and arrangement of parts may be 15 sorted to without departing from the spirit of the invention, or the scope of the subjoined claims.

Having thus described my invention, I claim:

20 1. A sand reel drive comprising a drive shaft, a sand reel shaft, means for driving said sand reel shaft from said drive shaft, said means comprising a friction clutch having one element fixedly mounted on said 25 sand reel shaft and a second element loosely mounted thereon, a brake band engaging said fixedly mounted element, and common control means for said brake band and said clutch, said means comprising a reciprocating lever, a pivotally mounted lever secured thereto, a second pivotally mounted lever connected to said first pivotally mounted lever, one end of said pivotally mounted

lever being connected to the loosely mounted element of said clutch, a brake operating lever connected to said first pivotally mounted lever, and connections between said brake band and said brake operating lever. 35

2. A sand reel drive, comprising a drive shaft, a sand reel shaft, means for driving 40 said sand reel shaft from said drive shaft, said means comprising a friction clutch having one element fixedly mounted on said sand reel shaft and a second element loosely mounted thereon, a brake band engaging 45 said fixedly mounted element, and common control means for said brake band and said clutch, said means comprising a reciprocating lever, a bell crank lever secured thereto, a pivoted lever secured to the opposite end 50 of said bell crank lever, the end of said pivoted lever being connected to the loosely mounted element of said clutch, a brake operating lever connected to said bell crank lever, a second bell crank lever connected to 55 the end of said brake operating lever, and connections between the ends of said brake band and the arms of said second bell crank lever.

In testimony whereof I affix my signature 60 in presence of two witnesses.

HAROLD J. LOCKHART.
